CLAIM

An ornamental design for a dispenser for lozenges, substantially as shown and described.

DESCRIPTION

FIG. 1 is a perspective view of a dispenser for lozenges showing my new design;

FIG. 2 is a front elevational view thereof;

FIG. 3 is a top plan view thereof;

FIG. 4 is a rear elevational view thereof;

FIG. 5 is a left side elevational view thereof; and

FIG. 6 is a right side elevational view thereof.
